(57) **CLAIM**

The ornamental designs for a container cover, substantially as shown and described.

DESCRIPTION

FIG. 1 is a top front perspective view of a container cover;
 FIG. 2 is a top back perspective view of a container cover;
 FIG. 3 is a front view of a container cover;
 FIG. 4 is a back view of a container cover;
 FIG. 5 is a right view of a container cover;
 FIG. 6 is a left view of a container cover;
 FIG. 7 is a top view of a container cover; and,
 FIG. 8 is a bottom view of a container cover.
 Portions shown in broken lines represent unclaimed portions
 of the claimed design.
